(57) **CLAIM**

I claim the ornamental design for a base for a decanting cradle, as shown and described.

DESCRIPTION

FIG. 1 is a perspective rear and left side view of a base for a decanting cradle showing my new design;

FIG. 2 is a left side elevational view thereof;

FIG. 3 is a second left side elevational view thereof;

FIG. 4 is a third left side elevational view thereof;

FIG. 5 is a fourth left side elevational view thereof;

FIG. 6 is a right side elevational view thereof;

FIG. 7 is a second right side elevational view thereof;

FIG. 8 is a front elevational view thereof;

FIG. 9 is a second front elevational view thereof;

FIG. 10 is a rear elevational view thereof;

FIG. 11 is a second rear elevational view thereof;

FIG. 12 is a top plan view thereof;

FIG. 13 is a second top plan view thereof;

FIG. 14 is a bottom plan view thereof; and,

FIG. 15 is a second bottom plan view thereof.

The broken line showing of a bottle basket in FIGS. 1, 3-5, 7, 9, 11, 13 and 15 is included for the purpose of illustrating environmental structure that forms no part of the claimed design.

1 Claim, 8 Drawing Sheets
